UNITED STATES PATENT OFFICE.

VOLEY A. JOHNSON, OF IRONTON, OHIO, ASSIGNOR OF ONE-HALF TO LAWSON BLENKINSOPP, OF LEXINGTON, KENTUCKY.

DOOR STRUCTURE.

Application filed August 23, 1923. Serial No. 659,010.

To all whom it may concern:

Be it known that I, VOLEY A. JOHNSON, a citizen of the United States, residing at Ironton, in the county of Lawrence and State of Ohio, have invented certain new and useful Improvements in Door Structures, of which the following is a specification, reference being had to the accompanying drawings.

This invention relates to certain improvements in door structures and has relation more particularly to a structure of this general character especially designed and adapted for use in mines and it is an object of the invention to provide a novel and improved structure wherein a door is mounted for swinging movement and for sliding movement relative to the path of travel of a mine car or other vehicle so that said vehicle may readily have reversed travel or movement in the event the vehicle has not entirely passed beyond the door.

Another object of the invention is to provide a novel and improved structure of this general character comprising two doors supported at opposite sides of the trackway for both sliding and swinging movement together with means for normally maintaining said doors in a closed position transversely of the trackway.

The invention consists in the details of construction and in the combination and arrangement of the several parts of my improved door structure whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a top plan view of my improved mine door structure;

Figure 2 is an elevation of the frame and of the doors;

Figure 3 is a perspective view of one of the doors looking toward one face thereof;

Figure 4 is a section on the line 4—4 of Figure 2;

Figure 5 is a fragmentary elevation look-

ing at the opposite side of the door from that shown in Figure 3;

Figure 6 is an elevation of the lower portion of the door and its supporting structure showing the ball bearings of the door in section;

Figure 7 is a section on the line 7—7 of Figure 2;

As disclosed in the accompanying drawings, M denotes a mine level tunnel or other passage way upon the floor of which is disposed a trackway T for the travel of mine cars or kindred rolling stock.

My improved door structure is adapted to be positioned within the level M or the like at such points desired but for the purpose of disclosure only a single structure is disclosed.

My improved structure comprises a frame structure S positioned within the level M or the like and disposed transversely thereof. As herein disclosed the frame S consists of a bottom sill 1 extending below the trackway T and extending a desired distance beyond each side of said trackway. The extremities of the sill 1 have extended upwardly therefrom the posts 2 of desired height, the upper end portions of said posts being connected by a top cap or beam 3.

Arranged at opposite sides of the trackway T are the vertically disposed posts 4 preferably piping and said posts have their opposite end portions in threaded engagement with the plates 5 and 6. The lower plate 5 is suitably engaged with the sill 1 while the upper plate 6 is engaged with the top cap or beam 3.

Associated with each of the posts 4 is a frame F. This frame F comprises a vertically disposed rear member 7 and the upper and lower members 8 and 9. The upper member 8 is of a length materially greater than that of the lower member 9 and each of the members 8 and 9 is pivotally connected as at 10 with the posts 4 through the instrumentality of a bearing 11, said bearing being to one side of the member 8 or 9. The lower bearing 11 has co-acting therewith suitable anti-friction means 12 whereby the frame F may be caused to swing with a minimum of frictional resistance with respect to its associated post 4.

The upper member 8 of each of the frames

F is substantially U-shaped in cross section with the side flanges 14 thereof downwardly disposed and the lower marginal portions of said flanges 14 are defined by the inwardly directed flanges 15 provided along their opposed marginal portions with the upstanding flanges 16. Arranged at spaced points lengthwise of each of the flanges 15 and rotatably supported by the flanges 14 and 16 are the rollers 17, the upper portions of said rollers being disposed above the free longitudinal margin of the flanges 16.

The lower member 9 is also of substantially U-shaped construction in cross section with its side flanges 18 upwardly disposed.

Associated with each of the frames F is a solid door D of sheet steel or other suitable material the upper marginal portion of the door being freely received between the flanges 16 and provided along its top with the oppositely directed flanges 18 resting upon the rollers 17 whereby the door D may have free sliding movement with respect to the frame F yet having swinging movement with said frame. The outer portion of the lower margin of the door D is also received between the flanges 18 of the lower member 9 whereby it is assured that the door D will be maintained in proper position with respect to the frame F. The inner portion of the lower margin of the door D is cut away as at 19 a distance sufficient to permit the door when in its normal position to properly extend over the trackway T and such lower portion of the door D has suitably secured thereto a sub-frame 20.

The inner vertical marginal portions of the door D and the lower portions thereof have secured to the opposite faces of the door the buffers 21 of steel or other suitable material and with which a car or the like travelling over the trackway T is adapted to contact as will hereinafter be more particularly referred to.

Extending rearwardly and outwardly from opposite sides of the upper portion of the member 7 of each of the frames F are the arms or brackets 22 to each of which is secured an extremity of a flexible member 23, each of said members being disposed over a guide roller or pulley 24 carried by the upper portion of the adjacent post 2. The members 23 extend downwardly a predetermined distance below the guide rollers or pulleys 24 and are connected to a single cable 25. Attached to the lower portion of the cable 25 is a weighted member 26 which serves to normally maintain the frame F substantially at right angle to the adjacent portion of the trackway T.

Each of the doors is constantly urged outwardly through the medium of a weighted member 27. This member 27 is secured to a flexible member 28 extending upwardly ad-

jacent to a post 4 and passes over a guide roller or pulley 29 carried by the upper portion of said post. The flexible member 28 is then directed toward the rear portion of the door D and secured thereto. By this means the door D is constantly urged outwardly so that under normal conditions of the door it is properly disposed across the trackway T.

As before stated the weighted members 26 serve to hold the frames F and the doors D carried thereby across the trackway T and also to hold the doors D or more particularly the frames F against swinging movement under the influence of air pressure within the mine level or kindred passage way.

The rear portion of each of the doors D comprises an extended part 31 preferably of tin whereby the weight of a door in its entirety is materially reduced.

As the car travels over the trackway T in either direction it will strike the doors D or more particularly the buffers 21 whereby the doors will properly swing into open position to permit the desired passage therebetween of the car. In the event it should be necessary to stop the car when passing between the doors D and back up, this desired operation may be readily accomplished because when the car is between the doors the inner vertical edges thereof will be in contact with the sides thereof and as the car travels rearwardly the doors D will be forced inwardly of the frames F sufficiently until the frames F together with the doors are free to swing in the requisite direction to permit an unobstructed travel of the car and after the car is free of the doors, the second weighted members 27 will automatically move the doors outwardly while the weighted members 26 will return the frames F together with the doors D to their normal position.

From the foregoing description it is thought to be obvious that a door structure constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A door structure comprising a frame, means for supporting the frame for swinging movement, means for holding said frame in a predetermined position, a door slidably supported by the frame, and means for urg-

ing said door to its outermost position with respect to the frame.

2. A door structure comprising a frame, means for supporting said frame for swinging movement, means for normally maintaining the frame in a predetermined position, a sliding door carried by the frame, automatic means to maintain the door in closed position.

10 3. A door structure comprising a frame, means for supporting said frame for swinging movement, automatic means for normally maintaining the frame in a predetermined position, a door slidably supported by the frame, and automatic means for normally maintaining the door at the limit of its sliding movement in one direction.

4. A structure of the class described comprising a post, a frame supported by the post for swinging movement, a door slidably supported by the frame, a flexible member secured to the rear portion of the door, a guide carried by the post with which the flexible member engages, and a weighted member secured to the flexible member, said weighted member and flexible member op-

erating to normally maintain the door at the limit of its sliding movement in one direction.

5. A structure of the class described comprising a frame, means for supporting the frame for swinging movement, oppositely disposed arms carried by the frame, flexible members secured to said arms, guide means for the flexible members supported independently of the frame, and a weighted member secured to the flexible members, said weighted member coacting with the flexible members to normally maintain the frame in a predetermined position.

6. In combination with a trackway, frames supported at opposite sides of the trackway for swinging movement, means for normally maintaining said frames in alignment and disposed in a direction across the trackway, sliding doors carried by the frames, and means for automatically moving the doors one toward the other.

In testimony whereof I hereunto affix my signature.

VOLEY A. JOHNSON.
